(57) **CLAIM**

I claim the ornamental design for a laundry sorter cart, as shown and described.

DESCRIPTION

FIG. 1 is a perspective view of a laundry sorter cart, showing our new design with laundry bags omitted from a frame for clarity of illustration;

FIG. 2 is a perspective view thereof with the laundry bags included;

FIG. 3 is a front elevational view of FIG. 2, the rear elevational view being a mirror image thereof;

FIG. 4 is a left-side elevational view of FIG. 2;

FIG. 5 is a right-side elevational view of FIG. 2;

FIG. 6 is a top plan view of FIG. 2; and,

FIG. 7 is a bottom plan view of FIG. 2.
